UNITED STATES PATENT OFFICE.

OSMUND M. JORSTAD, OF EAST PITTSBURGH, PENNSYLVANIA, ASSIGNOR TO WESTINGHOUSE ELECTRIC & MANUFACTURING COMPANY, A CORPORATION OF PENNSYLVANIA.

OVERHEAD TROLLEY SYSTEM.

Application filed April 7, 1922. Serial No. 550,362.

My invention relates to overhead trolley systems and it has particular relation to such trolley systems as are subjected to great changes in temperature and other loadings.

One object of my invention is to maintain the range of stresses in the contact wire of an overhead trolley system within relatively narrow limits, regardless of the loading thereon.

Another object of my invention is to provide means for automatically compensating for changes in the loading of such contact conductors.

A third object of my invention is to so position the compensating means in the overhead trolley system that it will not cause any irregularities in the under running surface of the contact wire.

Still another object of my invention is to provide a rugged and simple overhead trolley system that shall be economical of construction and positive and reliable in operation.

Briefly speaking, my invention consists in providing flexible or adjustable means, or both, for the contact wire to balance changes in loading thereon caused by changes in temperature, wind-pressure, and snow and ice loading.

For a better understanding of my invention, reference may be made to the accompanying drawings,

Figure 1 of which is a view, in side elevation, of a portion of a trolley system constructed in accordance with my invention;

Figs. 2 and 3 are views, partly in side elevation and partly in section, of devices employed in the overhead trolley system illustrated in Fig. 1;

Fig. 4 is a view, similar to Fig. 1, of a modified form of overhead trolley system in which my invention is employed; and

Figs. 5 and 6 are views, in plan and in side elevation, respectively, of a plurality of conductors that are illustrated in Fig. 1 of the drawing.

Referring particularly to Fig. 1 of the drawings, a plurality of trolley conductors 1 and 2, which alternately serve as messenger cables and as contact wires, are suspended, one from another, by means of a plurality

of hangers 3 and both are supported from a main cable 18 by means of a plurality of hangers 19. The main cable 18 is suspended from supporting structures 4 by means of suitable insulators 5. Springs 6 may be attached to the cables at points just removed from the plane of the traveling contact device or they may be employed to secure the trolley conductors to the hangers 19.

Each of the springs 6, (see Fig. 2) comprises a body member 8, a cap 9 provided with an eye 10 and a movable guide member 11, having a rod 12 secured thereto. At the opposite end of the rod 12 is an eye 13. The movable member 11 is biased toward the cap member 9 by a helical spring 14. The spring 14 may also serve to electrically connect the body member 8 to the movable member 11.

The turnbuckle device 7 (see Fig. 3), comprises two threaded bolts 15, mounted in a threaded holding member 16. Each of the bolts 15 is provided with an eye 17. In usual practice, a flexible shunt connection around each of the springs 6 and turnbuckle devices 7 would be provided.

Spring 6 may also be positioned in the messenger cable at points midway between the hangers 19, if such position is found so to be more satisfactory for the particular system that is constructed. Turnbuckles 7 may be substituted for the springs 6 but will not provide the automatic compensation for changes in loading that is effected when the springs 6 are employed. However, the turnbuckle 7 and spring 6, together, would be most satisfactory where the trolley system is subjected to extreme variations in temperature and loading and where the turnbuckles may be readily adjusted.

For a better understanding of how the trolley conductors 1 and 2 are positioned, reference may be made to Figs. 5 and 6 of the drawings, which illustrate the manner in which the trolley conductor 1 changes from a contact wire to a messenger cable at the same time that trolley conductor 2 changes from a messenger cable to a contact wire. It is to be understood that a material may be employed for the conductors 1 and 2, at places where they serve

as contact wires, that is different from the material employed where they function as messenger cables.

It is to be understood that the invention is equally applicable to systems where a plurality of trolley conductors are employed to simultaneously supply a relatively large value of current to a movable contact device, such, for example, as a pantograph.

10 In such a case, the wires will be suspended in parallel relation, one to another.

Referring to Fig. 4 of the drawings, the weight of the spring 6 may be removed from the trolley conductor that serves as a messenger cable at any given location by having the spring 6 suspended from the insulator 5 by means of a plurality of tension members 21 that are movably secured to a hanger 22.

20 From the above description, it is apparent that the adjustable devices provided by my invention for an overhead trolley system may be so arranged as to materially lessen the change in stress that occurs when 25 the trolley system is subjected to great variations in loading because of changes in temperature, snow, wind or ice loading. It is also apparent that these devices may be placed at points in the trolley system that 30 differ from those illustrated, without departing from the spirit of the present invention. It is desired, therefore, that my invention be limited only by the scope of the appended claims, as expressed by their 35 terms.

I claim as my invention:—

1. In a trolley system, the combination with a main cable and means for supporting said main cable, of a plurality of trolley 40 conductors, means for alternately supporting one of said conductors from another, means for suspending said conductors from said cable, and resilient means secured to said conductors to compensate for changes 45 in the loading thereof.

2. In a trolley system, the combination with a main cable, and means for supporting said main cable, of a plurality of trolley conductors, means for alternately supporting 50 one of said conductors from another, means for suspending said conductors from said cable, and flexible means secured to said conductors to compensate for changes in the loading thereof.

55 3. In a trolley system, the combination with a main cable, and means for supporting said main cable, of a plurality of trolley conductors, means for alternately supporting one of said conductors from another, 60 means for suspending said conductors from said cable, and adjustable means secured to said conductors to compensate for changes in the loading thereof.

65 4. In a trolley system, the combination with a main cable, and means for supporting

said main cable, of a plurality of trolley conductors, means for alternately supporting one of said conductors from another, means for suspending said conductors from said cable, and a spring secured to one of 70 said conductors to compensate for changes in the loading thereof.

5. In a trolley system, the combination with a main cable, and means for supporting said main cable, of a plurality of trolley 75 conductors, means for alternately supporting one of said conductors from another, means for suspending said conductors from said cable, and a turnbuckle secured to one of 80 said conductors to compensate for changes in the loading thereof.

6. In a trolley system, the combination with a main cable, and means for supporting said main cable, of a plurality of trolley 85 conductors, means for alternately supporting one of said conductors from another, a plurality of hangers for suspending said conductors from said cable, and a spring attached to one of said conductors between 90 said hangers to compensate for changes in the loading of said conductors.

7. In a trolley system, the combination with a main cable, and means for supporting said main cable, of a plurality of trolley 95 conductors, means for alternately supporting one of said conductors from another, a plurality of hangers for suspending said conductors from said cable, and a turnbuckle attached to one of said conductors between 100 said hangers to compensate for changes in the loading of said conductors.

8. In a trolley system, the combination with a main cable, and means for supporting said main cable, of a plurality of trolley 105 conductors, means for alternately supporting one of said conductors from another, a plurality of hangers for suspending said conductors from said cable, and a spring for securing one of said conductors to said 110 hanger.

9. In a trolley system, the combination with a main cable, and means for supporting said main cable, of a plurality of trolley 115 conductors, means for alternately supporting one of said conductors from another, a plurality of hangers for suspending said conductors from said cable, and a turnbuckle for securing one of said conductors to said hanger.

10. In a trolley system, the combination 120 with a main cable, of a messenger cable, a plurality of hangers for securing said messenger cable to said main cable, a contact wire, a plurality of hangers for securing said wire to said messenger cable, a spring 125 attached to said messenger cable, a plurality of tension members for supporting said spring and a hanger for supporting said tension members.

11. In a trolley system, the combination 130

with a main cable, of a messenger cable, a plurality of hangers for securing said messenger cable to said main cable, a contact wire, a plurality of hangers for securing said wire to said messenger cable, a turnbuckle attached to said messenger cable, a plurality of tension members for supporting

said turnbuckle and a hanger for supporting said tension members.

In testimony whereof, I have hereunto ¹⁰ subscribed my name this 27th day of March, 1922.

OSMUND M. JORSTAD.
